UNITED STATES PATENT OFFICE.

WILLIS D. WILLIAMS, OF KIRKLAND, ARIZONA TERRITORY, ASSIGNOR OF
ONE-HALF TO W. M. CLARK, OF WAGONER, ARIZONA TERRITORY.

RAIL-JOINT.

SPECIFICATION forming part of Letters Patent No. 765,535, dated July 19, 1904.

Application filed April 9, 1904. Serial No. 202,456. (No model.)

To all whom it may concern:

Be it known that I, WILLIS D. WILLIAMS, a citizen of the United States, residing at Kirkland, in the county of Yavapai, Arizona Territory, have invented new and useful Improvements in Rail-Joints, of which the following is a specification.

This invention relates to rail-joints, the object of the invention being to provide what may be termed a "boltless" rail-joint, or, in other words, one in which the usual bolts are dispensed with and the adjacent rail ends securely clamped between the oppositely-located parts of the joint, the joint members being so constructed, arranged, and disposed with relation to each other and to the rail ends that any weight, such as that of a moving train, imposed upon the rails adjacent to the joint will have the effect of causing the parts of the joint to firmly grip the rail ends and prevent any relative vertical, lateral, or longitudinal movement of the same.

With the above and other objects in view, the nature of which will more fully appear as the description proceeds, the invention consists in the novel construction, combination, and arrangement of parts, as hereinafter fully described, illustrated, and claimed.

In the accompanying drawings, Figure 1 is a side elevation of a rail-joint embodying the present invention. Fig. 2 is a vertical cross-section through the same, showing the oppositely-located members of the joint in elevation. Fig. 3 is a reduced plan view of the joint. Fig. 4 is a cross-section through the joint, taken adjacent to one of the flanges of the presser-block.

Like reference-numerals designate corresponding parts in all the figures of the drawings.

Referring to the drawings, 1 designates adjacent railway-rails of the ordinary construction embodying the head, web, and base flanges. The rail ends may either meet on a substantially straight joint, as shown at 2, or on a beveled or mitered joint, as shown at 3. The rail-joint contemplated in this invention comprises a base-plate 4, which is adapted to straddle and rest upon adjacent ties 5 and be-

secured thereto by means of the usual spikes 50 6. At one side a brace 7 extends upward from the base-plate and is shaped on its inner face to correspond with the side contour of the rail ends, as clearly shown in Fig. 2, so as to form an efficient support for the rail 55 ends at one side.

At the opposite side the base-plate 4 is provided with an upwardly-projecting back-stop 8, having a slanting inner surface 9, which is set slightly oblique to a vertical 60 plane for a purpose which will hereinafter appear. The back-stop or bracing-shoulder is cut away, as shown at 10, to provide slots for the reception of a corresponding number of flanges or reinforcements 11, which extend 65 outward and downward from a presser-block 12, which in operative position, has its outer face set at a slightly-inclined angle with respect to a vertical plane and the inner face thereof shaped to conform to the adjacent and 70 contacting side of the rail ends, as clearly shown in the sectional view, the said block being so shaped as to bear firmly against the base-flange, web, and under side of the rail-head. The lower extremities of the flanges or 75 reinforcements 11 terminate in the same plane with the bottom of the base-plate, and therefore rest directly upon the upper surface of the ties 5, the latter thus serving to hold the presser-block in proper position. While the 80 lower extremities of the flanges are practically flush with the bottom of the base-plate 4, a slight space may be left under the lower ends of the flanges, so as to provide for a slight downward movement of the presser-block under the weight of a train passing over the joint. 85

From the foregoing description it will be seen that the presser-block is held in proper relation to the back-stop by means of the flanges 11 and that by reason of the wedging 90 action between the presser-block and back-stop due to the disposition of the inclined meeting shoulders of the block and back-stop when pressure in a downward direction is applied to the rail ends adjacent to the joint the 95 tendency is to crowd the presser-block downward, such downward movement being accompanied by the crowding inward of the

block in firmer clamping engagement with the rail ends. Thus the greater the weight imposed on the rail ends the firmer will said ends be clamped between the presser-block and the 5 oppositely-lying brace 7. By preference the flanges 11 are made quite heavy, so as to form an effective brace at that side of the joint upon which the presser-block and back-stop are located. The rails are combined with the 10 members of the joint by sliding the same longitudinally into engagement therewith.

Having thus described the invention, what I claim as new is—

1. The combination with rail ends, of a joint 15 comprising a base-plate, a brace extending upward therefrom at one side of the rail ends, a back-stop extending upward from the base-plate at the opposite side of the rail ends, and a presser-block having a wedging fit between 20 the rail ends and back-stop and provided with outwardly-projecting flanges which engage the back-stop.
2. The combination with rail ends, of a joint 25 comprising a base-plate, a brace extending upward therefrom and engaging the rail ends at one side, a back-stop extending upward from the base-plate at the opposite side of the rail ends, and provided with one or more slots, and a presser-block having a wedging fit be- 30 tween the back-stop and rail ends and provided with one or more flanges which are received in the slot or slots in the back-stop.
3. The combination with rail ends, of a joint

comprising a base-plate extending beneath the rail ends and resting on adjacent ties, a brace 35 extending upward from the base-plate and engaging the rail ends at one side, a back-stop extending upward from the base-plate at the opposite side of the rail ends, and a presser-block having a wedging fit between the back- 40 stop and rail ends and provided with outwardly-extending flanges which engage the back-stop and also engage the ties.

4. The combination with rail ends, of a joint 45 comprising a base-plate passing under the rail ends, a brace extending upward from the base-plate and engaging the rail ends at one side, a back-stop extending upward from the base 50 at the opposite side of the rail ends and provided with a slanting shoulder, and a presser-block fitting between the back-stop and rail ends and provided with a slanting shoulder which engages the slanting shoulder of the back-stop for crowding the presser-block toward the rail ends when weight is imposed 55 thereon, said presser-block being provided with outwardly-extending flanges which engage the back-stop and also rest in contact with the ties.

In testimony whereof I affix my signature in 60 presence of two witnesses.

WILLIS D. WILLIAMS.
